UNITED STATES PATENT OFFICE.

ARTHUR E. CASE, OF CHICAGO, ILLINOIS, ASSIGNOR TO DELTA ELECTRIC COMPANY,
OF MARION, INDIANA, A CORPORATION OF INDIANA.

COIN-COLLECTOR FOR TELEPHONES.

1,110,669.

Specification of Letters Patent. Patented Sept. 15, 1914.

Application filed August 8, 1912. Serial No. 714,019.

To all whom it may concern:

Be it known that I, ARTHUR E. CASE, a resident of Chicago, in the county of Cook and State of Illinois, have invented certain 5 new and useful Improvements in Coin-Collectors for Telephones, of which the following is a full, clear, and exact description.

The present invention relates to toll-telephone systems and designs to provide an 10 improved system in which no extra labor is imposed upon the exchange operator in handling the toll or token deposited in payment for telephone service.

The invention provides a system in which 15 the coin is automatically disposed of, as a result of the usual manipulation of the system by providing coin-controlling devices which are operated by the act of removing the plug for making the disconnection at 20 the exchange, which is utilized to control the disposition of the coin, so that it will be deposited into the coin box, if the desired service is given. In attaining this object, the shift of the switch-hook at the sub-station 25 is utilized to determine the disposition of the coin. By removing the plug or making disconnection at the exchange, while the receiver is off the sub-station switch-hook, which is connected to the usual supervisory 30 signal at the central exchange, the operator, in making disconnection will automatically cause the coin to be refunded, and by waiting until the receiver at the sub-station has been placed on the switch-hook and then 35 making disconnection, the exchange-operator will cause the coin to be deposited into the coin-box.

An important characteristic of this system is, that if no service is given, for example, if 40 the calling line is out of operative condition the coin will be automatically refunded without any act upon the part of the exchange-operator.

The invention consists in the several novel 45 features hereinafter set forth and more particularly defined by claims at the conclusion hereof.

In the drawings: Figure 1 is a diagrammatic view of a telephone system embodying the invention. Fig. 2 is a front eleva-

tion, parts being shown in section or removed of the coin box at the sub-station and the parts therein. Fig. 3 is a section taken on line 3—3 of Fig. 2. Fig. 4 is a detail plan section of some of the parts. Fig. 5 55 is a side-elevation the cover being shown in section. Fig. 6 shows coin-deflector out of refunding action.

The invention is shown embodied in a toll-telephone system comprising a central-exchange A, a sub-station B, and a sub-station C. The exchange-equipment comprises a switch-board including spring-jacks 9 and 10, one for each sub-station, a cord-loop connected to plugs 11 and 12, each comprising 60 a tip and a sleeve-contact, a battery 13 connected to a conductor 14 between the sleeve-contacts of plugs 11 and 12 and to a conductor 15 between the tip-contacts of plugs 11 and 12. A line-signal 16 is included in a conductor 17 which is connected to loop-conductor 14, and a switch 18 operated by a line-magnet 19 which is included in a conductor 20 leading from conductor 17 to a contact 23 normally engaging the tip-contact 70 of the spring-jack 9. Switch 18 is connected to a conductor 21 which is connected to a loop-conductor 15 and to a conductor 22 which leads to a contact 24 normally engaging the sleeve-contact 75 of jack 9. The other side of the cord-loop is similarly connected to spring-jack 10 and a line-signal 16' is included in a conductor 17' which is connected to loop-conductor 14' and terminates at a contact adapted to be 80 engaged by a line-signal switch 18' which is operated by an electro-magnet 19' which is included in a conductor 20' which connects conductor 17' to a contact 23', which normally engages the tip-contact of jack 10. 90 Switch 18' is connected to a conductor 21' which is connected to a loop-conductor 15' and to a conductor 22' which extends to a contact 24' which normally engages the sleeve-contact of jack 10. Line-conductors 95 26 and 27 extend from the spring-contacts of jack 9 to sub-station B and conductors 26' and 27' extend from the contacts of jack 10 to the sub-station C.

The equipment at each sub-station com- 100

prises a switch-hook 30, a transmitter 31, a receiver 32 connected to the line in usual manner, and a toll-box 90 containing a polarized magnet 36 and a magnet 37. Line-conductors 27 and 26 lead to terminal posts 38 and 39 respectively. Transmitter 31 is included in a conductor 40 leading from a switch-hook contact 41, to a terminal 42. A terminal-post 43 is connected to another contact 44 at the switch-hook, by a conductor 45. Switch-hook 30 is connected to terminal-post 39, by a conductor 46.

The helix of an electro-magnet 81 for operating a supervisory signal 82, is included in each side of the loop-conductor 14. Suitable connections, which may be the same as usual are provided for causing the supervisory signal to be actuated to indicate when the receiver at the sub-station is off the hook, or the line is interrupted at the switch-hook contacts, as well understood in the art. A supervisory-signal is provided for each side of the cord-loop, that is, one for the answering, and another for the calling side.

The helices of polarized magnet 36 are included in a conductor 47 which leads from terminal-post 43 to terminal-post 38. The aggregate resistance of these helices is about 30 5000 ohms. A conductor 48 leads from a switch-contact 49 to one helix of magnet 36 to provide a path including a portion of the helix to interpose a low resistance, say 150 or 200 ohms. Contact 49 is adapted to engage a contact 50 which is connected by a conductor 51 to terminal-post 39. This switch comprising contacts 49, 50, is adapted to be operated and held in operative position or closed by a coin deposited into a 40 coin-channel 52 (Fig. 2) to cause a circuit to be established for the operation of the line-signal 16 at the exchange.

When the subscriber removes the receiver 32 from hook 30, a circuit will be established 45 which will be closed at contacts 49, 50 when a coin is deposited. Deposit of a coin into channel 52 will cause it to engage a roller 53 on switch-contact 49 to move said contact into engagement with its associated contact 50, and thereupon a circuit will be established 50 which will cause the operation of the line-signal 16 at the exchange. Said circuit will be as follows: battery 13, conductors 15, 21, 22, contact 24, the sleeve-contact of jack 9, line-conductor 26, post 39, conductor 51, contacts 50, 49 which are held in contact by the suspended coin, a conductor 48, a portion of one of the helices of polarized magnet 36, (so the resistance will amount to about 150 55 ohms) a portion of conductor 47, post 38, line-conductor 27, the tip-spring of jack 9, contact 23, conductor 20, including the helix of magnet 19, conductors 17 and 14 to battery 13. This circuit will cause magnet 60 19 to operate armature-switch 18 to close a

circuit in which line-signal 16 is included, which is as follows: battery 13, conductors 15, 21, switch 18, signal 16, conductors 17 and 14 to said battery. Thus, removal of the switch-hook at the calling-station is 70 necessary, and deposit of a suitable coin into the toll-box must be made to cause the coin to close switch 49, 50 before the line-signal will become operative to indicate that service is desired. Since deposit of a coin is 75 required in order to operate the line-signal at the exchange, the system is of the pre-payment type.

The low resistance of that portion of one helix of magnet 36, which is included in the 80 line-signal circuit, is insufficient to prevent the operation of magnet 19.

When the operator inserts plug 11 into spring-jack 9 in response to line-signal 16, the supply of potential of the line-magnet 81 will be cut off and the polarity of battery 13 with respect to the line-conductors will be reversed. Insertion of the plug establishes a circuit for speech transmission between the exchange and sub-station B. The deposited coin is held in position to close switch 49, 50 by a stop 54 which is operated by magnet 36 and withdrawal of this stop 54 causes the coin to be dropped onto a second stop 55, where it will remain suspended until the coin is to be refunded or cashed. The circuit for causing magnet 36 to operate stops 54 and 55 to cause the coin to fall from stop 54 and be held upon by stop 55, will be as follows: battery 13, conductor 15, tip of plug 11, the tip-contact of jack 9, conductor 27, post 38, conductor 47, (including both helices of magnet 36), post 43, conductor 45, contact 44, switch-hook 30, conductor 46, post 39, line-conductor 26, 105 sleeve-contact of jack 9, sleeve of plug 11, conductor 14 (including the helix of magnet 81), to battery 13. When the plug is inserted in spring-jack 9, the line-signal circuit is interrupted at the jack-contacts 23 and 24 110 and current of reversed polarity causes magnet 36 (Fig. 3) to repel its armature 56 so that coin-stop 54 will be moved to release the deposited coin, and the second coin-stop 55 will be rendered operative to receive and hold the coin. The falling of the coin to the second stop causes the spring-contacts 49 and 50 to separate. This energization of magnet 36 operates its armature 56 to shift a pair of switch-contacts 61, 66 into engagement with contacts 62, 79, respectively. Armature 56 is normally held in its centralized position by a spring 56^a. These operations put the system in condition for speech-transmission between the exchange 120 and the calling-station. The circuit for speech-transmission will be as follows: battery 13, conductor 14, sleeve of plug 11, sleeve-contact of jack 9, line-conductor 26, post 39, conductor 46, switch-hook 30, con- 125 130

ductor 40 (in which transmitter 31 is included), post 42, a conductor 60, switch-contacts 61 and 62, a conductor 63, post 38, line-conductor 27, tip-contact of jack 9, tip of 5 plug 11, conductor 15, battery 13.

At the same time that a talking circuit is being established, magnet 37 is short-circuited until contact 66 is separated from a contact 67. An armature 68 of magnet 37 10 carries a lever 69 (Fig. 2) for operating the coin-deflector 70 which is adapted, in one of its alternative positions, to deflect a coin falling from stop 55, into a refunding channel 71, (Fig. 3) and in its other position to 15 direct the coin into the cash-box 72. The purpose of short-circuiting this coin-controlling magnet 37 is to prevent the subscriber from refunding the coin by hanging up the receiver or pulling down the 20 switch-hook before central plugs in, when magnet 36 has been operated and the line-signal at the exchange has been actuated as herein before set forth, also to enable it to retain its slow-acting feature when the 25 plug is removed at the exchange with the sub-station receiver on the hook. Magnet 37 is included in a conductor 75 between a post 43 and switch-contact 66, and contact 67 is connected to a conductor 76 which leads 30 to post 43. A conductor 78 connects post 39 to a switch-contact 79 adapted to be engaged by contact 66 when the latter is shifted from its normal position by magnet 36. Switch-contact 62 is connected to post 35 38 by a conductor 63.

Switches 61, 66 and circuits are operated by armature 56 of polarized magnet 36 when said armature is shifted into position assumed when the exchange-operator has inserted 40 plug 11 into jack 9 and talking-conditions have been established as hereinbefore set forth. These switches cause the coin-controlling magnet 37 to be short-circuited when the receiver is off the hook at 45 the sub-station.

The purpose of short circuiting this magnet 37 is to make it possible to have different line-conditions when the plug is in the jack, and when the receiver is off the hook, 50 so that when the receiver is placed on the hook, while the plug is in the jack, the coin will be deposited in the cash-box, and when the receiver at the sub-station is placed on the hook after the plug has been withdrawn 55 from the jack, magnet 37 will cause refund of the coin. Another purpose of placing the helix of magnet 37 in series with the helices of magnet 36, which occurs when the plug is in the spring-jack and the receiver 60 is on the hook, is to interpose a sufficient resistance, say 10,000 ohms in the circuit to cause the armature of magnet 81 for the supervisory-signal, (which is included in loop-conductor 14) to be operated 65 so that said magnet will be deenergized

when the receiver is on the hook, the armature of magnet 81 being connected to the supervisory-signal circuit in the usual manner, so that it will fall back to its normal position, (away from the magnet) when 70 the latter is deenergized, as occurs by interposition of such high resistance in the circuit.

If the desired service or connection is given to the calling subscriber, no special 75 act upon the part of the exchange-operator is necessary in connection with the disposition of the coin, and the line is permitted to remain in condition for speech-transmission, as hereinbefore set forth, at which 80 time the polarized magnet 36 is bridged around the talking set of the sub-station and the coin-controlling magnet 37 is short circuited from the line.

When service is rendered, the exchange-operator leaves the plug 11 in jack 9 until the supervisory-signal indicates that the receiver at the calling sub-station has been placed on the hook. This replacement of the receiver on the switch-hook is utilized 85 in the present invention, to place the line in such condition that the removal of the plug from the jack at the exchange, will automatically cause the coin-controlling magnet 37 to deposit the suspended coin into the 90 cash-box. On the other hand, if the exchange-operator should fail to get the desired connection for the calling-subscriber, it will only be necessary to withdraw the 95 plug from the spring-jack while the receiver at the calling-station is off the hook, and thereupon circuit conditions will be 100 established which will cause the coin-controlling magnet 37 to control deflector 70, so that the coin falling from the second 105 coin-stop 55 will be guided into the refunding-channel 71 and be returned. These circuits and conditions cause the coin to be deposited in the cash-box when the receiver is 110 placed on the switch-hook at the calling-station before the plug is withdrawn from the jack at the exchange. Assuming that talking conditions have been established as hereinbefore set forth and the receiver is placed on the switch-hook at the substation, 115 a circuit will be established as follows: battery 13, conductor 15, tip of plug 11, tip-contact of jack 9, line conductor 27, post 38, conductor 47 (including magnet 36), post 43, conductor 75 and magnet 37, switch-contact 66, 79, conductor 78, post 39, line conductor 26, sleeve contact of jack 9, sleeve-contact of plug 11, conductor 14, magnet 81, to battery 13. Under these conditions the 120 aggregate resistance of magnets 36 and 37 125 will be included in the line and will be sufficient to prevent passage of sufficient current to cause magnet 81 to become actuated for operating the supervisory-signal, and thus this condition will indicate to the exchange- 130

operator that the conversation is at an end and that disconnection should be made.

Sufficient current passes through this circuit, however, to energize magnet 37 sufficiently to operate its armature 68 to shift lever 69 to tilt deflector 70 against the force of a light spring 70^a, so that when the armature 56 of the polarized magnet 36 is deenergized and passes into its normal position, 10 the coin-stop 55 will release the coin and the latter will drop down behind deflector 70, and into the cash-box 72.

Polarized magnet 36 is deenergized to release the coin-stop 55 when the exchange-operator withdraws plug 11 from jack 9, at 15 which time, current from battery 13 through the plug is interrupted. When the exchange-operator pulls out the plug, current of opposite polarity passes over the line and 20 through the polarized magnet 36, to shift its armature to restore the switches 66, 61 controlled thereby, and in so doing, breaks the circuit at said switches, said circuit of opposite polarity being as follows: battery 25 13, loop-conductor 15, conductor 21, 22 contact 24, sleeve-contact of jack 9, line-conductor 26, post 39, conductor 78, contacts 79, 66, conductor 75, and the helix of magnet 37, post 43, and the helices of magnet 36, 30 post 38, line conductor 27, tip-contact of jack 9, contact 23 conductors 20, (including magnet 19), 17 and 14 to battery 13. Thereupon the armature 56 of magnet 36 will tend to pass to its reversed position and will pass 35 into its centralized normal position and will separate switch members 66 and 79.

Magnet 37 is a slow-acting magnet, being formed with a suitable copper head, so that it will hold deflector 70 a sufficient period to 40 cause the released coin from stop 55 to pass into the cash-box before deflector 70 is restored to its normal position (Fig. 3) as a result of the deenergization of magnet 37.

If the service desired cannot be given, the 45 operator will merely withdraw the plug 11, from jack 9, while the receiver at the sub-station is off the switch-hook, which will cause the coin to be refunded, because magnet 37 will not be energized if the receiver is off the hook. The current for the operation of polarized magnet 36 to operate the coin-stop 55 and restore armature 56 of said magnet to cause the separation of switch 66, 50 79 will be as follows: battery 13, loop-conductor 15, conductors 21, 22, contact 24, sleeve-spring of jack 9, line-conductor 26, post 39, conductor 46, hook 30, contact 44, conductor 45, post 43, conductor 47 and the 55 helices of magnet 36, post 38, line-conductor 27, tip-spring of jack 9, contact 23, conductors 20 (including magnet 19) 17 and 14 to battery 13. In this circuit, the coin-controlling magnet 37 will be short-circuited, 60 so that deflector 70 will remain in its normal 65

position, shown in Fig. 3 to direct the coin from the stop 55 into the refunding channel. When the receiver is placed on the hook at the calling station, this circuit is interrupted at contact 44 of the switch-hook and the circuit will remain broken until a coin is again deposited. 70

When the sub-station is used for an incoming call, the operator inserts the plug into the spring-jack and rings the station 75 in the usual manner. When the called subscriber removes the receiver from the switch-hook, current from battery 13, will flow as follows: battery 13, conductor 15, tip of plug 11, tip contact of jack 9, conductor 27, 80 post 38, conductor 47 (including magnet 36) post 43, conductor 45, contact 44, hook 30, conductor 46, post 39, line-conductor 26, sleeve-contact of plug 9, sleeve of plug 11, conductor 14, to battery 13. The potential 85 will be of such polarity that magnet 36 will operate its armature 56 to operate switch-springs 62, 61 to include the talking set in the circuit for speech-transmission, which will be as follows: from battery 13 to post 90 38 as last set forth, conductor 63, contacts 62, 61, conductor 60, post 42, conductor 40 in which the talking set is included, contact 41, switch-hook 30, conductor 46, to post 39 and thence back over line-conductor 26, as 95 heretofore set forth.

If it should be desired to signal to the exchange-operator from the sub-station by working the switch-hook 30 up and down to flash the supervisory signal, this may be 100 done without affecting the coin-controlling device, because the operation of the coin-stop 55 is only effected by withdrawal of the plug from spring-jack and not by shift of the hook. 105

The toll apparatus at the sub-station is 110 inclosed in a suitable case 90. Armature 56 is suitably pivoted at 91. Armature 68 is pivoted at 92. Coin-deflector 70 is pivoted on a pin 93 and has an extension 94 disposed 115 to be engaged by lever 69. Coin-stops 54 and 55 are both formed on a lever 95 which is pivoted at 96, and are disposed so that when said lever is in its normal position, the coin runway 52 is clear of said stops, and when armature 56 of polarized magnet 36 is shifted to one of its alternative positions by the circuit established upon deposit of the coin, stop 54 will be moved into the runway, and when the armature is shifted to the 120 other of its alternative positions, as occurs when the circuit is established for speech-transmission, lever 95 will withdraw stop 54 out of the runway and will shift stop 55 into the runway 52. Lever 95 is operated 125 by armature 56 by means of arm 95^a formed in such manner as to engage in a slot in abutment 97 (Fig. 4). Armature 56 has an abutment 97 for engaging switch-contacts 66, 61, to conjointly shift spring 66 out of 130

contact with spring 67 and into contact with spring 79, and to shift spring 61 into contact with spring 62. The walls of coin-channel 52 have openings 98 therein for coin-stops 54 and 55.

If the line is inoperative to cause the operation of the line-signal at the exchange by closing the circuit at contact 49, 50, when a coin is deposited, so that lever 95 will be operated by magnet 36 to shift coin-stop 54 into position to hold the coin, and keep the circuit closed at said contacts, the coin will fall through the coin runway and be deflected into the refunding channel 71, deflector 70 being normally in the position shown in Fig. 3. Therefore, if the line is out of operative condition to signal the exchange, the coin will be automatically refunded.

The invention thus exemplifies, a prepayment toll-telephone system in which disposition of a coin is automatically made, so that no special act upon the part of the exchange operator is necessary to dispose of the coin, because means and connections are provided whereby the disposition of the coin depends upon the two acts; that is, withdrawing the plug and placing the receiver on the hook, and when the plug is withdrawn with the receiver off the hook, the coin will be automatically refunded and when the subscriber hangs up the receiver before disconnection is made at the exchange, the system will automatically collect the suspended coin. In fact, the operation required by the exchange operator is the same as in a telephone system in which no provision is made for toll and the operation upon the part of the subscriber is the same, except that the prepayment of a coin is required to operate the line-signal at the exchange. It thus becomes possible for an exchange operator to handle as many calls in this toll-telephone system, as is possible in a system in which no provision is made for toll.

The invention is not to be understood as restricted to the details set forth since these may be modified by the skilled mechanic within the scope of the appended claims without departing from the spirit and scope of the invention.

Having thus described the invention, what I claim as new and desire to secure by Letters Patent, is:

1. A toll-telephone system comprising an exchange, a sub-station, a connecting line, a coin collecting device, and means and connections for controlling the coin-device to cause it to refund the deposited coin when the calling-line is disconnected at the exchange before the subscriber disconnects the sub-station at the sub-station.

2. A toll-telephone system comprising an exchange, a sub-station, a connecting line, a

coin collecting device, a coin-controlled switch at the sub-station, and means and connections for controlling the coin-device to cause it to refund the coin when the calling-line is disconnected at the exchange before the subscriber disconnects the sub-station at the sub-station.

3. A toll-telephone system comprising an exchange, a sub-station, a connecting line, a coin collecting device at the sub-station, a coin-controlled line-signal at the exchange, and means and connections for controlling the coin-device to refund the deposited coin, when the line is disconnected at the exchange, before the subscriber disconnects the sub-station at the sub-station.

4. A toll-telephone system comprising an exchange, a sub-station, a connecting line, a coin collecting device at the sub-station, a coin-controlled line-signal at the exchange, and means and connections for operating the coin-device to automatically refund the deposited coin when the line is disconnected at the exchange, before the subscriber disconnects the sub-station at the sub-station.

5. A toll-telephone system comprising an exchange, a sub-station including a telephone-set and a switch-hook, a connecting line, a coin-collecting device at the sub-station, and means and connections for controlling the coin-device to refund a coin when the calling-line is disconnected at the exchange before the subscriber places the receiver of the telephone-set on the switch-hook.

6. A toll-telephone system comprising an exchange, a sub-station including a telephone-set and a switch-hook, a connecting line, a coin-collecting device at the sub-station, a coin-controlled line signal at the exchange, and means and connections for controlling the coin-device to refund the coin deposited to cause the operation of the line-signal, when the calling line is disconnected at the exchange before the subscriber places the receiver of the telephone-set on the switch-hook.

7. A toll-telephone system comprising an exchange, a sub-station including a telephone-set and a switch-hook, a connecting line, a coin-collecting device at the sub-station, and means and connections for controlling the coin-device to refund a deposited coin, when the calling line is disconnected at the exchange, before the subscriber hangs the receiver on the switch-hook, said means comprising a polarized magnet connected to the line.

8. A toll-telephone system comprising an exchange, a sub-station including a telephone-set and a switch-hook, a connecting line, a coin-collecting device at the sub-station, a coin-controlled line-signal at the exchange, and means and connections for controlling the coin-device to refund a coin de-

6

posed in payment of toll, when the calling line is disconnected at the exchange, before the subscriber hangs the receiver on the switch-hook, said means comprising a polarized magnet connected to the line.

9. A toll-telephone system comprising an exchange, including a cord-loop, a sub-station including a telephone-set and a switch-hook, a connecting line, a coin-collecting device at the sub-station, and means and connections for causing the coin-device to refund the coin deposited in payment of toll, when the calling line is disconnected from the cord-loop at the exchange, before the subscriber hangs the receiver on the switch-hook, said means comprising a polarized magnet and a slow-acting magnet.

10. A toll-telephone system, comprising an exchange including a cord-loop, a sub-station including a telephone-set and a switch-hook, a connecting line, a toll-collecting device at the sub-station, a coin controlled line-signal at the exchange, and means and connections for causing the coin-device to refund the coin deposited in payment of toll, when the calling line is disconnected from the cord-loop at the exchange, before the subscriber hangs the receiver on the switch-hook, said means comprising a polarized magnet and a slow acting magnet.

11. A toll-telephone system comprising an exchange including a cord-loop, a sub-station including a telephone-set and a switch-hook, a connecting line, a coin-collecting device at the sub-station, a coin-controlled line signal at the exchange, and means and connections for operating the toll-device to automatically refund the coin deposited in payment of toll, when the calling line is disconnected from the cord-loop at the exchange, before the subscriber hangs the receiver on the switch-hook, said means comprising a polarized magnet and a slow acting magnet.

12. A toll-telephone system comprising an exchange, a sub-station including a telephone-set and a switch hook, a connecting line, a coin-collecting device, and suitable means and connections whereby the coin-device will be operated to cash the coin when the exchange is disconnected from the line, if the receiver is placed on the switch-hook at the sub-station before the line is disconnected at the exchange.

13. A toll-telephone system comprising an exchange, a sub-station including a telephone-set and a switch-hook, a connecting line, a coin-collecting device, and suitable means and connections whereby the coin-device will be operated to cash the coin, if the receiver is on the switch-hook at the sub-station when the line is connected at the exchange, and whereby the toll-device will be operated to refund the coin when

the line is disconnected at the exchange, when the receiver is off the hook at the sub-station.

14. A toll-telephone system comprising an exchange, a sub-station including a telephone-set and a switch-hook, a connecting line, a coin-collecting device, a coin-controlled line-signal, and suitable means and connections whereby the coin-device will be operated to cash the coin, if the receiver is placed on the switch-hook at the sub-station when the line is disconnected at the exchange, and whereby the coin-device will be operated to refund the coin when the line is disconnected at the exchange before the receiver is on the switch-hook at the sub-station.

15. A toll-telephone system comprising an exchange, a sub-station including a telephone-set and a switch-hook, a connecting line, a coin-collecting device, suitable means and connections whereby the coin-device will be operated to cash the coin when the receiver is placed on the switch-hook at the sub-station before the line is disconnected at the exchange, and whereby the coin-device will be operated to refund the coin when the sub-station is disconnected at the exchange, before the receiver is placed on the hook at the sub-station, and means at the exchange for indicating whether the receiver is on or off the switch-hook.

16. A toll-telephone system comprising an exchange, a sub-station including a telephone-set and a switch-hook, a connecting line, a coin-receiving device, and suitable means and connections whereby the disposition of a deposited coin by said device will be dependent upon the time when the receiver of the telephone-set at the sub-station is placed on the switch-hook, relatively to the time when the line is disconnected at the exchange.

17. A toll-telephone system comprising an exchange, a sub-station including a telephone-set and a switch-hook, a connecting line, a coin-receiving device, a coin-controlled line-signal at the exchange, and suitable means and connections whereby a deposited coin will be automatically disposed of by said device according to the time when the receiver of the telephone-set at the sub-station is placed on the switch-hook relatively to the time when disconnection of the line is made at the exchange.

18. A toll-telephone system comprising an exchange, a sub-station including a telephone-set and a switch-hook, a connecting line, a toll-collecting device at the exchange for indicating when the receiver is on the hook at the sub-station, and means and connections for controlling and operating the toll-device to automatically dispose of a coin into either of two paths, including a polarized magnet, means for causing

current of one polarity to energize said magnet when a coin is deposited, means for causing current of opposite polarity to energize said magnet when connection is made 5 with the line, at the exchange, in response to the line-signal, and a magnet in a circuit

controlled by said polarized magnet and the switch-hook.
